CLAIM

The ornamental design for a limb protector, as shown and described.

DESCRIPTION

FIG. 1 is a front elevational view of a limb protector showing my new design;

FIG. 2 is a left side elevational view thereof, the right side being a mirror image;

FIG. 3 is a rear elevational view thereof;

FIG. 4 is a top plan view thereof; and

FIG. 5 is a bottom plan view thereof.

*Fig. 1**Fig. 2**Fig. 3**Fig. 4**Fig. 5*
